UNITED STATES PATENT OFFICE.

HUGH L. WARNER AND WILLIAM H. LONSDALE, OF DAYTON, OHIO,
ASSIGNORS TO THE DAYTON MOTOR VEHICLE CO., OF DAYTON,
OHIO, A CORPORATION OF WEST VIRGINIA.

HYDROCARBON-BURNER.

SPECIFICATION forming part of Letters Patent No. 716,497, dated December 23, 1902.

Application filed July 25, 1901. Serial No. 69,679. (No model.)

To all whom it may concern.

Be it known that we, HUGH L. WARNER and WILLIAM H. LONSDALE, citizens of the United States, residing at Dayton, in the county of 5 Montgomery and State of Ohio, have invented certain new and useful Improvements in Hydrocarbon-Burners; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to new and useful improvements in hydrocarbon-burners, and possesses the advantages hereinafter described and claimed.

An object of the invention is to provide a 20 burner of the above type with an extra-high heating capacity and which is especially adapted to use in connection with boilers for generating steam for steam-carriages or automobiles and small steam-generators.

25 A further object of the invention is to provide a burner having the essential quality of durability and which is not liable to melt or become warped, is readily cleaned, a burner that will not "light back" or "burn back," 30 and thereby endanger the mixer-pipe or the detachable base.

In carrying out our invention it becomes an object to provide means for starting or vaporizing the fuel separately and independently 35 of the main burner, which is therefore necessary before the main burner can be used.

In carrying out the objects of our invention, which, broadly speaking, is to provide a burner that has a high degree of efficiency 40 and one which has special advantages that adapt it for use in connection with boilers for generating steam, we have paid particular attention to the details of construction, which are important factors in the attainment of the 45 ends desired. For example, we have paid attention to the means for generating the hydrocarbon gas before it is admitted to the main burner, and thereby avoid the discharge of the hydrocarbon to the burner in liquid 50 form. The generation of the gas occurs instantaneously with the admission of the oil to

the initial burner. We have also paid attention to the construction of the jet-openings in the main burner, with a view to overcoming the objections hereinbefore noted. We have, 55 further, taken into consideration the importance of not permitting air to enter between the upper edge of the burner and the lower end of the boiler.

It is well known to those familiar with 60 burners of the above type that more or less difficulty is experienced in keeping the small jet-openings through which the gas escapes to the flame open. These small openings as commonly constructed have a great tendency 65 to become stopped up with rust and a gummy substance composed of a mixture of vapor and dust accumulating on the interior walls surrounding said openings. This difficulty is greatly augmented by the great amount of 70 dust created below the vehicle, and the result is the efficiency of the burners now in use for steam-generation for motor-vehicles is greatly reduced.

Preceding a detailed description of our invention, reference is first made to the accompanying drawings, which fully illustrate the same.

Figure 1 is a top plan view of our improved hydrocarbon-burner intact. Fig. 2 is a front 80 elevation of the same. Fig. 3 is a side elevation, the rear portion broken away; Fig. 4, a side sectional elevation taken centrally through the burner. Fig. 5 is an enlarged section on the line $x-x$ of Fig. 6; Fig. 6, an 85 enlarged plan view of a portion of the burner surrounding one of the jet-openings; Fig. 7, an enlarged sectional view on the line $x'-x'$ of Fig. 6; Fig. 8, a top plan view of the generator. Fig. 9 is a front elevation of the same, 90 the door being removed; Fig. 10, a detached view of the generator-burner; Fig. 11, a detail of the fuel-distributing pipe. Fig. 12 is a top plan view of the burner, in which is shown some modifications in the construction 95 thereof. A portion of the top plate is broken out in this view. Fig. 13 is a sectional elevation of the burner, in which are shown some modifications in the construction of the bottom or base plate. Fig. 14 is a section on the 100 line $y-y$ of Fig. 12.

In the specification similar letters of refer-

ence indicate corresponding parts in the drawings.

The main burner is preferably circular in form and consists of top and bottom plates A 5 and B, which are united by a surrounding wall C. Projecting from the bottom plate is a series of tubes B', which are joined to the top plate by ears, as shown clearly in Figs. 6 and 7. There is an annular space e on each 10 side of the ears a, into which washers a' fit. The upper ends of the tubes B' are reduced in diameter, as at b, to provide suitable supports for the washers a'. These washers have their under sides tapered in the direction of 15 the annular jet-openings e, which openings are provided by said washers. The washers are removable when it is desired to clean the burner. The advantage of the under tapered surfaces of said washers lies in the 20 fact that the ascending currents of gas are directed immediately to the gas-openings e around said washers. While we have shown the annular gas-openings e surrounding the outer circumference of said washers, it is 25 readily seen that these openings may be arranged on the inner sides of said washers or the washers themselves may be made to contain the jet-openings. It will be understood that the gas circulates throughout the interior 30 of the burner on all sides of the tubes B'. The bores or openings B'' of said tubes enable a proper circulation of air above the jet-openings in the burner.

C' designates a mixer-tube which is projected 35 into the burner to the distance substantially as shown in Fig. 4. The lower side of this tube is cut away, as at C'', to allow the proper discharge to the interior of the burner at a central point in said burner. The inner 40 end of said tube is closed by a wall E, which deflects the incoming gas out of the cut-away portion of said tube.

D designates a supporting-rim, which may be an integral part of the burner, or it may be 45 detachable, as in the present case. This rim is mounted on top of the burner and affords a support for the boiler. (Not shown.) The lower edge of said rim is provided with an annular bead or flange F'', which has an annular groove F' therein to receive asbestos packing consisting of a cord G', whereby an air-tight joint or connection is made between the burner and the rim. The upper edge of 50 said rim is also provided with a flange F, having a groove D' to receive asbestos cord G, by means of which an air-tight connection is made between the boiler and the rim D, the bottom of the boiler resting on the asbestos cord. The burner and the rim are connected 55 by suitable bolts I, secured to the rim with their lower ends projected through lugs I' on the side of the burner and receiving tightening-nuts I''. The boiler may be secured to the rim in any desired manner—such, 60 for example, as by the flanges K, which project from the said rim. It has not been thought necessary to illustrate the boiler in

the drawings, as it forms no part of the present invention, and the mounting of the same on the burner is easily understood.

Referring to Fig. 12, this shows a maximum size of burner—for example, a burner of twenty inches diameter. This size of burner is constructed on the same principles as the smaller sizes, as shown in Figs. 1, 2, and 3. 75 In order to supply the larger-size burner with the necessary quantities of gas, two mixer-tubes C' C' are placed therein. These mixer-tubes are fed from the nozzle O⁶ by means of a T-fitting R, which is connected to said nozzle O⁶ and discharges into the two mixer-tubes through nipples S.

In order to enable boilers to be cleaned without having to remove or detach the burner, we provide an opening T in the center of the 85 burner, which is normally closed by a plug, as shown in Figs. 12 and 14. The upper portion g of said plug has a tapering surface, which fits against a similar surface surrounding said opening in the top plate. The lower 90 portion h of said plug has screw-threads which engage with the threads in the opening in the bottom plate B. The two plugs g and h are connected by bars i. A plug usually closes an opening in the bottom of the 95 boiler. This is a well-known feature of boilers of the type for which these burners are intended. Therefore an illustration of the same has not been deemed necessary. It may be stated, however, that said boiler-plug 100 is in the center of the bottom of the boiler, immediately above the opening T in the burner, which opening, as before stated, is normally closed by the plugs g and h. Whenever it is desirable to remove the boiler-plug 105 for any purpose, the plugs g and h may be easily removed by means of a wrench and access then had to the boiler-plug. This is a feature of very great convenience, as it saves 110 the time and labor incidental to the removal of the burner in order to get at the boiler-plug.

Referring to Fig. 13, the bottom plate B is provided with an annular oil-channel u on its top side. This channel, as will be seen, 115 gradually inclines and deepens as it approaches the front of the burner, where it will be seen to have a greater depth. It therefore follows that any oil entering the burner through the mixertube or tubes C' will gravitate to that portion of the burner and will discharge through a pipe u', which communicates with the front of the channel u. The said tube u' therefore will serve to drain the burner of all oil entering it. This is an important feature, owing to the fact that in the use of burners for motor-vehicles, boats, &c., there is more or less danger of the initial or generator burner going out or becoming extinguished in unobserved moments. The 120 consequence of this is that the main burner is soon flooded with oil, and thus becomes a source of danger, as an explosion will naturally follow when the generation of gas takes 125

place. By providing the drain - channel u and pipe u' it will be seen that the oil will be at once conducted from the burner. The drip-pipe u' is very close to the receiving end 5 of the mixer-tube C' . This is desirable from the fact that when gas is entering the burner through the mixer-tube any portion thereof which may find its way into the pipe u' will be quickly drawn into the receiving 10 end of the mixer-tube and thence back into the burner under the suction created by the gas entering the mixer-tube. Therefore there will be no perceptible loss of gas through said pipe u' when the burner is in operation.

15 J designates a thimble secured to the rim D through ears J' in a position above the mixer-tube C' . This tube J telescopes with a similar tube N , which projects from the generator or pilot-house L . Within the tube 20 N there is a generating-coil H' , which is the terminal of an oil-supply pipe H . The coil H' may be projected as far across the face of the burner as may be desired. This feed-pipe H lies above the upper surface of the burner 25 and connects with a tank or other source of supply. (Not shown.) The coil H' may be formed as shown in Fig. 8, or the coils may extend lengthwise or parallel with the tube N . The tube N is rigidly secured to the back of 30 the pilot-house L and provides a connection and support therefor with the burner. Within this exterior compartment, which we have termed a "pilot-house," a generation of gas for the main burner takes place through the 35 means presently described and which means are amply illustrated on Sheet 3 of the accompanying drawings. The coils H' , it will be seen, occupy the space of the tube N , and the inner end H of said coil projects into or connects with a neck O , which is a part of a fuel-distributing pipe of peculiar shape, as shown 40 in Fig. 11. The downwardly-extended portion O' of said pipe terminates in another right-angled portion O'' , which passes through 45 a side wall of the pilot-house and provides for a valve-fitting M , through which a valve-stem M' passes, the valve controlling the admission of fuel to the initial burner. (Shown in Fig. 10.) It will be understood that a valve 50 is located within the depending tube O' at the junction of the extension O'' . P is a drip-cup, into which oil is discharged through said valve for the initial burner to flame. Before referring further to the initial burner, Fig. 55 10, we will complete the description of the fuel-distributing pipe, Fig. 11.

O^3 is a tubular extension projecting at a right angle from the upper end of O' and communicating therewith. This extension O^3 60 joins a further extension O^4 , which extends obliquely and terminates in a discharge-nozzle O^6 , that projects through the rear wall of the pilot-house and feeds the mixer-tube C' , as shown in Fig. 3. The upper end of the 65 oblique extension O^4 provides for a valve-fitting M'' , through which a valve-stem M^3 passes

to a valve which controls the discharge of gas to the mixer-tube C' .

The initial burner, as shown in Fig. 10, consists of two right-angled portions Q and Q' , 70 the former of which projects into the coils H' and forms the main heating medium for said coils. Referring to Fig. 10 of the drawings, it will there be seen that the extension Q' occupies an upright or vertical position and 75 the horizontal or burner portion proper extends at a right angle from said upright portion. It may be said, however, that the upright or vertical portion Q' may be dispensed with by terminating it at a point adjacent to 80 the horizontal portion Q , the latter portion constituting the burner and supplying the necessary initial heat. The rear end of said initial burner is closed by a wall Q^8 , which is provided with jet-openings f , as are also the 85 sides of said burner. The upright portion Q' terminates in a nozzle Q'' , which projects in proximity to the valve end of the pipe O' , from which it receives fuel. The nozzle Q'' is connected to pipe O' by means of lugs c 90 and d . The pilot-house L is provided with a door L' , hinged at L'' . In the upper portion of said door there is an opening L''' , which is closed by a panel of glass or other transparent material. This sight-opening is in line 95 with the upper portion of the initial burner Q Q' . Therefore the flame is always visible, and the accidental going out thereof may be quickly detected. Owing to the differences in the construction of motor-vehicles, it is 100 impossible to have a fixed relative position of the pilot-house with the burner. We therefore have provided means for varying the position of the pilot-house when such becomes necessary. These means consist of the telescopic 105 connections J and N , hereinbefore referred to, which form an adjustable connection between the burner and the pilot-house.

It is obvious that the pilot attachment shown on Sheet 3 of the drawings may be 110 applied to other burners for use in connection with steam-boilers, and while we consider that our burner has many desirable advantages we do not wish to be restricted to the use of our pilot attachment therewith. 115 On the contrary, we desire to claim said pilot-house broadly in combination with hydrocarbon-burners.

The operation of the burner is briefly described as follows: The drip-cup P is provided 120 with oil through the valve M' for the initial burner or generator, Fig. 10. This initial burner causes the vaporization of the oil and forms a gas, which is admitted through the distributing-pipe, Fig. 11, by means of valve 125 M^3 , the said gas being discharged to the mixer C' .

Having described our invention, we claim—

1. In a hydrocarbon-burner, a burner the base of which has a series of tubes projected 130 therefrom, and the top plate of which has a corresponding series of openings into which

- said tubes project, and a washer of less diameter than said openings mounted on the upper end of each of said tubes within the openings in said top plate, whereby there is provided a series of annular gas-jets surrounding said washers, substantially as specified.
2. In a hydrocarbon-burner, a burner the base of which has a series of tubes projected therefrom, and a top plate having a corresponding series of openings surrounding the upper ends of said tubes, a series of removable washers mounted on the upper ends of said tubes within the openings in the top plate, said washers lying flush with the upper surface of the top plate and reducing the openings therein so as to provide a series of annular gas-jets around said washers, substantially as specified.
3. In a hydrocarbon-burner, a burner the base of which is provided with a series of tubular extensions, a top plate united to the base and provided with a series of openings into which said tubular extensions project, connections between the opposite sides of said tubular extensions and the top plate, and a series of washers mounted on the upper ends of said tubular extensions, said washers lying within the openings in the top plate and providing a series of jet-openings around the circumference of said washers, substantially as described.
4. In a hydrocarbon-burner, a base-plate, a series of tubes projecting therefrom, a top plate united to the base-plate said top plate having a series of openings into which said tubes project, lugs connecting the upper ends of said tubes with the top plate, and a series of washers mounted on the upper ends of said tubes within the openings in the top plate, the said washers providing a series of annular gas-jet openings around the circumference thereof, substantially as specified.
5. In a hydrocarbon-burner, a burner the base of which is provided with a series of tubular extensions, said tubular extensions being reduced at their upper ends to provide annular shoulders, a top plate having a series of openings therein into which the reduced ends of said tubes project, connections between said tubular extensions and said top plate, and a series of washers supported on the reduced ends of said tubular extensions within the openings in the top plate, a mixer-tube within said burner, and means for generating gas and supplying it to said mixer-tube, substantially as described.
6. In a hydrocarbon-burner, a burner comprising a base having a series of tubes projecting therefrom, a top plate united to said base and provided with a series of openings into which the ends of the tubes project, a series of washers of less diameter than said openings mounted on said tubes within the openings in the top plate, said washers having their under sides beveled whereby the gas is deflected to the annular jets surrounding said washers, substantially as specified.

7. As a new article of manufacture, a hydrocarbon-burner comprising top and bottom plates, a series of tubes interposed between said top and bottom plates and projected into openings in the top plate, a series of washers mounted on said tubes within the openings in the top plate, the said washers providing a series of gas-openings in the top plate around said tubes, substantially as specified.

8. In a hydrocarbon-burner, the combination of a burner having a series of tubes interposed between the bottom and top plates thereof, openings in the top plate surrounding said tubes, washers mounted on said tubes within said openings, said washers reducing the openings in said top plate and thereby providing a series of annular gas-openings around the circumference of said washers, a mixer-tube projected into said burner, and means exterior to the burner for generating gas consumed thereby, substantially as described.

9. As a new article of manufacture, a hydrocarbon-burner comprising a top and bottom plate, a series of tubes interposed between said plates and projected into openings in the top plate, lugs connecting said tubes to the top plate, washers mounted on said tubes within the openings in the top plate, said washers providing a series of gas-openings therearound, and means for initially generating gas for said burner, substantially as specified.

10. In a hydrocarbon-burner, a base-plate having a series of tubular extensions projected therefrom, a top plate having a series of openings therein into which said tubular extensions project, and washers surrounding said tubes and providing openings for the passage of gas from the burner.

11. In a hydrocarbon-burner, a base-plate having a series of tubular extensions projected therefrom, a top plate having a series of openings therein into which said tubular extensions project, washers surrounding said tubes and providing openings for the passage of gas, an initial gas-generator for said burner, and a pilot-house in which said gas-generator is inclosed.

12. In a hydrocarbon-burner, the combination of a burner having a series of tubes interposed between the top and bottom plates of said burner, openings in the top plate surrounding said tubes, washers of less diameter than said openings mounted on said tubes within said openings said washers reducing the openings in the top plate and thereby providing a series of gas-openings around the tubes, and one or more mixer-tubes projected into said burner.

In testimony whereof we affix our signatures in presence of two witnesses.

HUGH L. WARNER.

WILLIAM H. LONSDALE.
